[57] CLAIM

The ornamental design for a video spine label, as shown and described.

DESCRIPTION

FIG. 1 is a front elevational view of the video spine label showing my new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof; and,

FIG. 7 is a perspective view thereof in a folded condition, the video tape depicted by means of broken lines being shown for illustrative purposes only and forming no part of the claimed design.
